UNITED STATES PATENT OFFICE

ROBERT A. BADGER, OF ROCHESTER, NEW YORK.

BOTTLE-PACKING.

No. 903,827.

Specification of Letters Patent.

Patented Nov. 17, 1908.

Application filed June 6, 1908. Serial No. 437,144.

To all whom it may concern:

Be it known that I, ROBERT A. BADGER, a citizen of the United States, residing at Rochester, in the county of Monroe and 5 State of New York, have invented certain new and useful Improvements in Bottle-Packing, of which the following is a specification.

This invention relates to packings for 10 bottles or other articles, said packings comprising a box or case in which transverse partitions are mounted, the said partitions having perforations which receive the bottles or other articles and prevent lateral movement of the latter in the box or case.

The object of my present invention is to 15 provide a structure having partitions or lateral supports of the general type shown in Patent 410,496, granted September 3, 1889, 20 to Simeon G. Curtice, but improved so as to facilitate the insertion of the partitions or lateral supports when the case is being packed.

In the patent referred to, the partitions 25 have notched corners forming flanges, the notches being rectangular ones so that the edges of each flange are parallel. When said flanges are bent or turned, two of them upward and two of them downward, the partition as a whole must be pushed into the packing case with great care in order to prevent the edges of the flanges from binding against the interior walls of the box or case. If the partition gets tilted during its insertion, the edges and corners of the flanges bind so as to obstruct and materially interfere with the operation of packing.

The object of my invention is to provide 30 an improved form of partition or lateral support which cannot bind when it is being inserted in the box or case even if it is tilted considerably.

To these ends my invention consists in the 35 construction and combination of parts substantially as hereinafter described and claimed.

Of the accompanying drawings in which 40 similar reference characters indicate the same or similar parts in all of the views:— 45 Figure 1 represents a vertical sectional view through a box or case having my improved partition or lateral support located therein, some of the bottles being also shown in said figure. Fig. 2 is a similar view but at a 50 right angle to Fig. 1. Fig. 3 is a plan view of a blank before its flaps have been folded.

Said figure shows the blank employed for the upper partition in Figs. 1 and 2, it being understood that the blank employed for the lower partition is preferably similar excepting that two of its flaps are longer. 60

The sides of the box are indicated at A and B, and the top and bottom at C, the box being shown as containing bottles D, some of which in practice are inserted right end 65 up and others inverted. The drawings show only the inverted bottles. The arrangement of bottles will be, in practice, practically the same as in the Patent 410,496, above referred to. 70

The upper partition or lateral support E comprises a sheet of straw board or other suitable material the body of which is perforated to permit the bottles to be inserted, said sheet being scored or creased to form 75 flanges e and e'. In carrying out my invention, the blank or sheet E has its corners cut away as at e² so as to form beveled inclined ends of the flanges, resulting in the formation of each flange with an outer or free edge 80 of less length than the length of its base portion where it joins the body of the partition. The beveling or cutting may be in a straight line or more or less curved. Two of the flanges e are turned upward and the other 85 two flanges e' are turned downward. The lower partition or lateral support F also has four flanges, two of which are turned upward as at f' to meet the down turned flanges e' of the partition E, the other two 90 flanges f of the partition F being turned downward to rest on the bottom of the box. In Figs. 1 and 2 I have indicated that the flanges f f' are also beveled or inclined as at f², but I do not limit myself to a structure 95 having two partitions the flanges of both of which are beveled or inclined. Since the lower partition is inserted in the box before any bottles are placed therein, it is easier to manipulate said partition when locating it, 100 and it may not always be necessary to bevel the edges of the flanges of the lower partition. 105

As indicated in the drawing the relative lengths of the flanges e', f' are such that 110 they meet in a plane considerably above the mid depth of the box, this proportion being practically the same as in the patent above referred to. But it is to be understood that I do not limit myself to the relative lengths of the flanges since they may be so proportioned as to meet at any point between the

two partitions. It will be understood of course, that the flanges e' and f' are employed to prevent the partitions from shifting toward each other, while the flaps e and f preserve the partitions at the desired distances from the top and bottom of the box.

It will not be understood that owing to the beveling or inclination of the ends of the flanges as shown in Fig. 3, when said flanges 10 are bent in opposite directions so as to stand perpendicular to the body of the partition and the partition is to be inserted in the box, the ends of said flanges can not bite into or bind against the inner surfaces of the sides 15 of the box even if the partition is considerably tilted out of a plane parallel with the top of the box. This is because each flange is what may be termed tapering, since its outer or free edge is of less length than its 20 base or line of junction with the body or horizontal portion of the partition.

Having now described my invention, what I claim is:—

1. As a means for sustaining articles against lateral movement in a packing case, 25 a partition having a perforated body and flanges perpendicular to said body, the outer edge of each flange being of less length than its base.

2. The combination with a packing case, 30 of a perforated partition having four flanges two of which are turned upward and two downward along the inner walls of the case, the outer edge of each flange being of less length than its base. 35

In testimony whereof I affix my signature, in presence of two witnesses.

ROBERT A. BADGER.
